INVENTOR,

UNITED STATES PATENT OFFICE.

ROBERT L. DORAN, OF CHICAGO, ILLINOIS.

HEATING PLANT.

1,338,361.

Specification of Letters Patent. Patented Apr. 27, 1920.

Application filed January 9, 1919. Serial No. 270,359.

To all whom it may concern:

Be it known that I, ROBERT L. DORAN, a citizen of the United States of America, and a resident of Chicago, county of Cook, and 5 State of Illinois, have invented certain new and useful Improvements in Heating Plants, of which the following is a specification.

The main objects of this invention are to provide an improved form of heating plant 10 for utilizing heavy fuel oils for miscellaneous heating purposes and particularly for house heating; to provide an improved arrangement of the parts suitable for use in the fireboxes of coal and wood stoves and 15 furnaces; to provide an improved form of burner having a battery of units each of which is adapted to be independently operated; to provide improved means for controlling the admission of fuel to each of said 20 units, whereby the heat may be regulated from a distance; and to provide an improved form and arrangement of the generating means and sub-flame or pilot burners.

An illustrative embodiment of the invention is shown in the accompanying drawings, in which—

Figure 1 is a perspective view of the improved burner arranged for use in a house-heating furnace.

Fig. 2 is a fragmentary view of a house-heating system equipped with the improved burner and having the control valves located at a distance from the furnace.

Fig. 3 is a longitudinal sectional view of 35 one of the units, taken on the line 3—3 of Fig. 1.

Fig. 4 is a transverse sectional view of one of the units.

In the construction shown in the drawings, the improved heating plant comprises 40 a series or battery of burner units 3 each of which is complete in itself and adapted to be independently controlled, and a pilot system 4 which is independently operated for pre- 45 heating the generators of each of said units.

Each of the units 3 as shown in Fig. 3 comprises a burner tube 5 having a generator 6 mounted thereon, one end of said burner tube communicating with said generator 50 through a mixing chamber 7. The generator 6 is in the form of a vaporizing tube having one end supported by a clip 8

mounted at the front end of the burner tube, the other end of said vaporizing tube engaging an aperture formed in a shield 9, 55 said shield being rigidly secured to the units at the rear ends thereof for holding them in a definite spaced relation. An asbestos wick 10 is mounted in the vaporizing tube, which also has at its outlet end a wire 60 gauze 11 for filtering the vaporized fuel as it passes from the wick to the mixing chamber 7. The forward end of the vaporizing tube communicates with the fuel supply through a conduit 12. The mixing chamber 7 is a hook-shaped member one end of which has threaded engagement with the burner tube 5, the other end being spaced a slight distance away from the open or rear end of the generator so as to provide an air 65 inlet. A plurality of openings or outlets 13 are formed in the burner tube in which are loosely mounted nozzles 14, supported by shoulders 15 positioned so as to permit said nozzles to lie flush with the rims of the outlets. Inasmuch as they are surrounded by 70 rims of iron and are substantially flush with the iron, the nozzles are protected against injury. The nozzles 14 are foraminous, 75 disk-shaped blocks of refractory material, 80 such as lava, with a multiplicity of fine closely spaced perforations distributed over them. A deflector 16 is secured to the burner tube by screws 17 in a position to direct the flame from the burner upwardly 85 in a sheet. The burner tube has a plurality of gas outlet slots 18 formed in the upper wall thereof for supplying heat to the generator 6. A plate 19 is mounted on the side of the burner tube adjacent the gas outlet slots so as to more effectively direct the 90 heat against the vaporizing tube 6.

The pilot system is complete in itself, being operated independently of the main units, and comprises a plurality of sub-flame burners 20 communicating with a 95 pilot generator 21. The sub-burners are mounted on arms which communicate with the generator through a conduit 22 and are located in position to heat the respective 100 generators 6 of the main burners 3. Refractory nozzles are carried in the outlets of the sub-burners and are of the same construction as the nozzles 14 of the main

burners. The pilot generator 21 is similar in construction to the generators 6 and communicates with the fuel supply through a conduit 23, the flow of fuel being controlled by a valve 24. The vaporizing tube 21 is supported at one end by a brace 25 connected to the oil inlet valve fitting 24 and at the other end by an air inlet fitting 26, the brace and fitting 26 being both attached 5 to a burner tube 27 disposed beneath the vaporizing tube 21. The burner tube 27 communicates with the vaporizing tube through a mixing chamber 28. The burner tube 27 has some asbestos wicking embedded in a trough 29 formed thereon, to hold a quantity of liquid fuel for preheating the generator tube 21 on starting, and also a plurality of gas outlet slots 30 for supplying heat to the vaporizing tube when the fuel in 15 the trough has been consumed.

The parts are all arranged compactly upon standards 1 and 2 so that the device is suitable for use within the firebox of any of the usual coal and wood stoves and 20 ranges and can be readily inserted or removed, as may be desired.

In the operation of the device, the generator 21 is preheated by fuel in the trough 29, whereupon the valve 24 is opened to permit 30 the flow of fuel to the generator 21. The gas formed in this generator passes to the sub-burners 20 where it is ignited. When the generators 6 have been sufficiently heated by the flame from the sub-burners, 35 the valves 31 controlling the flow of fuel to the units may be opened. In the arrangement shown in Fig. 2, the burner is seated in the firebox of a furnace, and the valves for regulating the flow of fuel to the units 40 are located at a distance from the heating plant. A tank 32 of fuel under pressure is provided for supplying liquid fuel to the burner, said tank being connected to the pilot generator 21 by a tube 33 and to the unit valves 31 by a tube 34. The pilot or 45 sub-burners may thus be kept burning continuously during the cold season of the year, except when it becomes necessary to refill the tank 32. The number of units in operation is controlled by the valves 31, which 50 may be located at a distance so that it is unnecessary to go to the furnace for regulating the heat of the plant. Small metal tubes known as hollow wire are capable of 55 delivering oil fast enough for the ordinary house-heating plant. These may be led anywhere like wires and need no protecting conduits or insulation as do electric wires.

By reason of the peculiar composition and 60 form of the nozzles 14, they become incandescent when heated, and provide a concentration of radiated heat much more intense than the usual flame of a hydrocarbon burner and more uniform for heating and 65 cooking purposes. The effect is similar to

that of a bed of glowing coals at the best stage of a coal fire. With this form of nozzle, the fuel is entirely burned and no free carbon will be deposited on the burner.

The feature of using refractory material 70 as a nozzle for a burner of this type is described and more broadly claimed in my co-pending application, Serial No. 270,360, filed of even date herewith.

Although but one specific embodiment of 75 this invention has been herein shown and described, it will be understood that numerous details of the construction shown may be altered or omitted without departing from the spirit of this invention as defined by the following claims.

I claim—

1. A hydrocarbon burner, comprising a hollow body having a surface studded with outlets, foraminous refractory blocks seated 85 in said outlets so as to lie flush with the surface of said body, a generator for supplying a gaseous mixture to said outlets, said body having a plurality of gas outlet apertures formed therein for heating said generator, 90 a sub-burner located in position to heat said generator, a pilot generator for supplying a gaseous mixture to said sub-burner, means for preheating said pilot generator and means whereby said generators are controlled independently of each other. 95

2. A hydrocarbon burner comprising a battery of burner units, a plurality of generators for supplying a gaseous mixture to said units, means for controlling the supply 100 of fuel to said generators whereby they are independently operated, a plurality of sub-burners located in position to heat said generators respectively, a pilot generator for supplying a gaseous mixture to said sub-burners, means whereby all of said generators are controlled independently of each other. 105

3. A heating plant comprising a battery 110 of main burner units, a plurality of generators for supplying a gaseous mixture to said units, a plurality of sub-burners located in position to heat said generators respectively, a pilot generator for supplying a gaseous mixture to said sub-burners and 115 means located at a distance from the heating plant for controlling the supply of fuel to each of said main burner generators, whereby they may be operated independently of each other, and means adjacent to 120 the heating plant for controlling the supply of fuel to said pilot generator.

4. A burner comprising a plurality of independently operated units, a plurality of generators for supplying a gaseous mixture 125 to said units, said units having slots formed therein for heating said generators, deflectors mounted on said units adjacent said slots, refractory nozzles mounted on said units and adapted to be heated to incandes- 130

cence by the flame issuing therefrom, deflectors rigidly mounted on said units adjacent said nozzles, sub-burners located in position to heat said generators, refractory nozzles 5 mounted on said sub-burners and adapted to be heated to incandescence by the flame issuing therefrom, a pilot generator for sup- plying a gaseous mixture to said sub-burners and means for controlling the flow of fuel to said generators whereby they are independently operated. 10

Signed at Chicago this 27th day of December 1918.

ROBERT L. DORAN.
